(57) **ABSTRACT**

Disclosed is a cleaning device that comprises a first arm portion with an adjustable length, a first cleaning portion, a second arm portion supporting the first cleaning portion, and a rotating adjustable portion located between the first arm portion and the second arm portion, the first arm portion being rotatable in a predefined range about the second arm portion.

**CROSS REFERENCE TO RELATED
APPLICATIONS**

This application is a national stage filing under 35 U.S.C. 371 of PCT/US2011/053445, filed Sep. 27, 2011, which claims priority to Chinese Patent Application No. 201020552262.6, filed Sep. 28, 2010, the disclosures of which are incorporated by reference in their entirety herein.

TECHNICAL FIELD

The present disclosed cleaning device comprises a first arm portion pivotally separated from a second arm portion, which supports a first cleaning portion.

BACKGROUND

Cleaning window panes is laborious and time-consuming work, especially on high rise buildings, where washing glass is not only difficult but also dangerous, thus it requires the service of specialized personnel.

A number of cleaning devices are provided in the prior art, such as the window cleaning device disclosed in U.S. Pat. No. 3,769,651, which comprises a U-shaped holder with a handle attached to one end and a cleaning head used for the cleaning of external windows attached to the other. The cleaning device disclosed in U.S. Pat. No. 3,769,651 is incapable of effectively cleaning upper story windows, however. U.S. Pat. No. 5,007,753 discloses a window cleaning apparatus that has a cleaning head that is rotatable to any position when used on a window surface; however, the angle of the handle is not adjustable. As a result, the apparatus is not adapted to clean of exterior windows.

SUMMARY

To overcome existing problems in prior art, the present disclosure provides a cleaning device, the cleaning device being adapted for the cleaning external windows and also the cleaning of external windows at different elevations. Moreover, the cleaning portion of the cleaning device achieves full contact with the glass surface, improving cleaning efficiency.

In one embodiment, the cleaning device comprises: a first arm portion having an adjustable length; a first cleaning portion; a second arm portion supporting the first cleaning portion; a rotating adjustable portion located between the first arm portion and the second arm portion wherein the first arm portion is rotatable in a predefined range about the second arm portion.

In one embodiment, the cleaning device further comprises: a second cleaning portion, said second cleaning portion being configured to mount detachably on the second arm portion. In one embodiment, the second arm portion is made from a flexible material. In one embodiment, the second arm portion takes the form of a "V" shape, and the second cleaning portion is mounted between the arms of the V-shaped second arm portion. In one embodiment, the rotating adjustable portion has a button, and pressing said button causes the first arm portion to rotate about the second arm portion. In one embodiment, hooks are disposed along the surface of the second cleaning portion, wherein the hooks are used for attachment of a cleaning cloth. In one embodiment, the second cleaning portion can be used independently, or may be used in combination with the first cleaning portion. In one embodiment, the predefined range is 0-180°. In one embodiment, the cleaning

2

device further comprises a bottle containing a foam cleaning agent is attached to said first arm portion.

BRIEF DESCRIPTION OF DRAWINGS

- 5 FIG. 1 is a front schematic view of an embodiment of a cleaning device;
10 FIG. 2 is a lateral schematic view of the cleaning device of FIG. 1;
15 FIG. 3 is a schematic view of the predefined angle of first arm portion rotation;
20 FIG. 4 is an enlarged partial view of the first cleaning portion and second cleaning portion;
25 FIG. 5 is a schematic view of the rotating adjustable portion;
30 FIG. 6 is a cross-sectional view of the rotating adjustable portion;
35 FIG. 7 is a cross-sectional view of the rotating adjustable portion;
40 FIGS. 8-11 are schematic views of components of the rotating adjustable portion.
45 While the above-identified drawings and figures set forth embodiments of the invention, other embodiments are also contemplated, as noted in the discussion. In all cases, this disclosure presents the invention by way of representation and not limitation. It should be understood that numerous other modifications and embodiments can be devised by those skilled in the art, which fall within the scope and spirit of this invention. The figures may not be drawn to scale.

DETAILED DESCRIPTION

The cleaning device 10 of the present disclosure comprises: a first arm portion 4, the first arm portion 4 having an adjustable length; a first cleaning portion 5, the first cleaning portion 5 being adapted for the cleaning of glass surfaces; a second arm portion 1, said second arm portion 1 providing support to the first cleaning portion 5; a rotating adjustable portion 3, the rotating adjustable portion 3 being located between the first arm portion 4 and the second arm portion 1, the first arm portion 4 being rotatable in a predefined range about the second arm portion 1 by means of the rotating adjustable portion 3. In one embodiment, the predefined range is 0-180°.

45 The cleaning material mounted on the first cleaning portion 5 can be used for cleaning and also the absorption of liquid. During cleaning operations, the cleaning material can be detached when it becomes dirty, cleaned and then reattached to the first cleaning portion 5.

50 As shown in FIG. 3, the first arm portion 4 rotates about the second arm portion 1 to a predefined angle. The cleaning device can therefore be extended outside the building to clean the glass of external windows. In addition, the extendable rod of the first arm portion 4 can be used to adjust the length of the 55 first arm portion and thereby clean the glass of external windows at different elevations.

55 As shown in FIG. 1, the second arm portion may take the form of a "V" shape and be made from a flexible material, the flexible material being a rubber, thermoplastic elastomer or other resilient material. During cleaning operations, the flexibility of the second arm portion 1 enables full contact between the first cleaning portion 5 and the glass surface, reducing labour and improving the efficiency of cleaning operations.

60 In one embodiment, the cleaning device further comprises a second cleaning portion 2, which is detachably mounted on the second arm portion 1. In the present embodiment, the

second cleaning portion **2** is inserted between the arms of the second arm portion, as shown in FIG. 4. The second cleaning portion **2** can be used in combination with the first cleaning portion **5** or may also be used independently. Hooks may be disposed along the surface of the second cleaning portion **2** for attaching a cleaning cloth. The cleaning cloth is typically a non-woven fabric or other cleaning cloth, the scraping action of which is used to remove dirt.

As shown in FIG. 3, the rotating adjustable portion **3** has a button, and pressing said button causes the first arm portion **4** to rotate about the second arm portion **1** in a predefined range.

In one embodiment, the cleaning device further comprises a bottle containing a foam cleaning agent attached to the first arm portion **4**.

The rotating adjustable portion **3** shown is comprised of the following components: a first arm connecting portion **31**, a second arm connecting portion **32**, a button **33**, a locking piece **34** and a spring **35**, as shown in FIGS. 5-11. The button **33** and locking piece **34** are fixed together, and connect the first arm connecting portion **31** to the second arm connecting portion **32**. Referring to FIGS. 6-7 and 11, in the absence of any external force, the elastic force of the spring **35** acts to insert the projecting portion **341** of the locking piece **34** into the recessed portion **321** of the second arm connecting portion **32** and the recessed portion **311** of the first arm connecting portion **31**, locking the second arm connecting portion **32** and the first arm connecting portion **31** in place and preventing rotation; pressing the button **33** causes the projecting portion **341** of the locking piece **34** to slide outward, releasing the lock between the second arm connecting portion **32** and the first arm connecting portion **31**, leaving them free to rotate. Consecutive and corresponding recessed portions are disposed in the interiors of the second arm connecting portion **32** and the first arm connecting portion **31**, such that the second arm connecting portion **32** and the first arm connecting portion **31** can be locked at 30° intervals in a 0-180° range. An alternative number of recessed portions may also be disposed. Moreover, to ensure the strength of the locking connection, 4 projecting portions may be disposed symmetrically on the locking piece.

Method of use for the cleaning device: transfer the foam cleaning agent onto the second cleaning portion **2**, use the second cleaning portion **2** to perform cleaning operations on

the glass surface, then rotate the device 180° and use the first cleaning portion to remove the water and debris. When cleaning external windows, adjust the rotating adjustable portion, rotating the first arm portion about the second arm portion to a predefined angle, adjust the length of the first arm portion according to the position of the external window, then extend the cleaning device outside the building to clean the external window.

While particular embodiments of the present invention have been illustrated and described, a person of ordinary skill in the art will realize that these embodiments can be modified without departing from the principles and spirit of the present utility model, the scope of this invention being defined by the claims herein and their equivalents.

What is claimed:

1. A cleaning device comprising:
a first arm portion having an adjustable length;
a first cleaning portion;
a second arm portion supporting the first cleaning portion;
a second cleaning portion connected to the second arm portion, wherein the second arm portion takes the form of a "V" shape, and the second cleaning portion being detachably mounted between the arms of the V-shaped second arm portion; and
a rotating adjustable portion located between the first arm portion and the second arm portion that allows for the first arm portion to rotate in a predefined range about the second arm portion.

2. The cleaning device of claim 1, wherein the second arm portion is made from a flexible material.

3. The cleaning device of claim 1, wherein the rotating adjustable portion has a button, and pressing said button causes the first arm portion to rotate about the second arm portion.

4. The cleaning device of claim 1, wherein hooks are disposed along the surface of the second cleaning portion, said hooks being used for attachment of a cleaning cloth.

5. The cleaning device of claim 1, wherein said predefined range is 0-180°.
